ABSTRACT: A two-piece container closure which can be opened to form a dispenser. The closure includes a fixed part and a movable part which operates with the fixed part to open and close the dispenser. The fixed part top wall is provided with an opening and a skirt member downwardly directed from the peripheral area of the opening. The skirt member includes a plurality of downwardly, inwardly directed, spaced, separate flexible flanges. The movable part includes a valve member which comprises an imperforate base and sidewalls downwardly positioned from the top wall which are inwardly directed and provided with at least one dispensing opening. The movable part is positioned within the top wall opening for movement relative to the fixed part and so that the opening in the valve sidewalls will register with the spaces between the flanges in the dispensing position. The flanges are flexed downwardly by the valve member when the valve member is retained within the top wall opening. The downwardly flexed flanges are biased upwardly causing an intimate face contact between the valve member sidewalls and the flexible flanges.

MOLD EJECTION ASSEMBLABLE TWO-PIECE CAP

This is a division of copending application Ser. No. 541,202 now U.S. Pat. No. 3,461,488 issued Aug. 19, 1969.

This invention relates to dispensing containers and more particularly to a two-piece dispensing closure therefor. More specifically, the invention relates to a two-piece dispensing closure wherein one portion thereof is fixedly placed in relationship to the container and the other portion thereof is free to move relative thereto from an open dispensing position to a closed nondispensing position.

It is desirable that dispensing closures for fluid substances, such as free-flowing solids and liquids including detergents and the like, be easily manipulated from an open dispensing position to a closed nondispensing or sealing position and that such actuating movement be obvious and simple to the ultimate user. As such dispensing closures are primarily used in conjunction with throw-away containers, a further important factor is that such must be relatively inexpensive in order to gain widespread use. One of the major contributing factors to increased cost of such closures is the mechanical assembling procedures that must be carried out thereupon to place such in operating condition.

Hitherto before mechanical assembly of component dispensing closure portions, notwithstanding the highly sophisticated machinery used in this regard and the highly developed state of the art in general, has been time-consuming and costly through the necessity of at least one additional secondary operation. The present invention, however, contemplates the assemblage of the component parts of the present novel closure construction within the mold itself upon the opening and ejection cycles thereof in such a manner that no increase in the molding cycle of the closure is necessitated and the use of a secondary operation to assemble the closure is obviated.

With the above comments and other objects in view that will hereinafter appear, the nature of the invention will be more clearly understood by reference to the following detailed description, the appended claims and the several views illustrated in the accompanying drawings, wherein like numerals refer to like parts.

In the drawings:

FIG. 1 is a perspective view of the two-piece fluid dispensing container closure of the present invention shown in its assembled position;

FIG. 2 is an exploded perspective view of the closure shown in FIG. 1 with portions broken away for clarity;

FIG. 3 is a sectional view of the closure taken along the line 3-3 of FIG. 1 and shows the path of flow of fluid from the container area when such closure is in its open dispensing position;

FIG. 4 is a bottom view of the closure shown in FIGS. 1 and 3; and

FIG. 5 is an enlarged sectional view of a portion of the assembled closure showing the attachment portions thereof in greater detail.

Reference is now made to the drawings in detail and particularly FIGS. 1 through 5 thereof wherein a two-piece fluid dispensing container closure of novel construction is illustrated and referred to by the reference numeral 10. Such closure 10 comprises a fixed part 11 and a movable part 12 which is assembled therewith for relative movement thereto in a non-longitudinal direction so as to be alternatively positionable from a closed nondispensing position to an open dispensing position. While the movable part 12 in the drawings is shown in assembled position with the fixed part 11 so as to permit rotational movement thereto, it should be brought out that other movement such as nonlongitudinal slide motion or the like is equally acceptable and that the rotational aspect depicted in the drawing is for illustrative purposes only.

The fixed part 11 may be integral with a fluid container or separable as illustrated and may have a top wall portion 13 with downwardly depending sidewalls 14 integral therewith. The sidewalls may be internally provided with screw threads 15 or other equivalent means for attachment to the neck of a

conventional container and further be provided with sealing fins 16 or their like. The top wall is further provided with an opening 17 therethrough which has been illustratively shown as circular in the drawings to permit the rotational movement of the movable part 12 as contemplated; but as hereinbefore stated, the opening could be of other regular geometric configuration such as a rectangular slot wherein the relative movement of the movable part to the fixed part would be a lateral slide rather than rotation.

- 10 The top wall 13 is further provided about the periphery of the opening 17 therethrough with a slotted skirt member 18 extending downwardly and preferably inwardly from the inner side of such top wall 13 so as to be positioned inwardly of the peripheral extent of the opening at its lower terminus. Such slotted skirt member 18 is generally comprised of two or more downwardly inwardly extending flanges 19 separated from each other by slotted portions 20. The top wall 13 of the fixed part 11 is further provided with holding means 21 located around the periphery of the opening 17 in such a manner as to 15 captively hold the movable part in fixed longitudinal relationship thereto after the two components are assembled in a manner as will hereinafter be more clearly brought out. Such holding means 21 is shown by a circumferential bead 22 which inwardly extends into the opening 17 from the peripheral portions thereof and which is preferably provided with a gently sloped upper portion 23 to provide a lead-in for the assembling of the movable portions therewith in a cutaway area 24 positioned downwardly adjacent thereto.
- 20 The movable part 12 is comprised of a fluid dispensing portion 25, a valve member 26 and attachment means 27. The attachment means 27 permits the movable part to be assembled to the fixed part in such a manner to permit relative movement therewith to opening and closing positions and, furthermore, 25 to prevent relative longitudinal motion thereto and may comprise in part, as shown, a groove 28 at the outer periphery of the movable part at the junction of its fluid dispensing portion 25 and its valve member 26. A fluid dispensing portion 25 may take a generally cylindrical configuration and is preferably 30 provided at the other portion of its walls 29 with grooves or flutes 30 as a means by which the movable part may be grasped by the user of the device. The valve member 26 of the movable part generally extends entirely beneath the top wall 13 of the fixed part and is provided with sidewalls 31 adapted 35 for intimate engagement with the flanges 19 of the skirt 18. The sidewalls 31 terminate in a base portion 32 which is imperforate and imparts to the valve member 26 a general overall appearance of a truncated cone. The sidewalls 31 are further provided with at least one opening therethrough which is preferably orientated longitudinally thereof. In this manner then the intimate engagement of the valve member 26 with the skirt 18 when the openings 33 of the sidewalls are covered by the flanges 19 of the skirt 18 provides a nondispensing closed 40 position of the closure member 10 so as to confine fluid within the container. It may be seen that upon rotation of the movable part 12 in such a manner so as to at least partially align the openings 33 with the slots 20 of the skirt 18, an alternate open fluid dispensing position may be obtained. In this manner, by 45 the relative movement of the movable part 12 in regard to the fixed part 11, alternate open and closed positions may be obtained for desired access to closure of the container.

I claim:

1. A two-piece fluid dispensing container closure comprising; a fixed part in fluid sealing disposition with the contents retaining portion of said container said fixed part having a top wall, and a movable part operable with said fixed part to open dispensing and closed sealing positions, said top wall having an opening therethrough and a skirt member extending 50 downwardly from the peripheral area of said opening, said skirt member comprising a plurality of downwardly, inwardly directed, spaced, separate flexible flanges, said movable part being positioned within said top wall opening for movement relative to said top wall, said movable part having a valve member including an imperforate base and sidewalls,

downwardly positioned from said top wall and inwardly directed, said sidewalls being provided with at least one dispensing opening, said opening registering with at least one of the spaces between said flanges in the dispensing position, said flanges being in intimate face contact with said valve member sidewalls so that movement of said valve member can align one of the spaces between said flanges and said sidewall opening in a dispensing position, and misalign said spaces and said opening in a closed position and means for operatively retaining said sidewalls and said flanges in said intimate contact.

2. The container closure as set forth in claim 1 wherein said top wall opening is circular, said movable part having a

generally cylindrical fluid dispensing portion positioned generally outwardly of said top wall and wherein said retaining means is provided at the inner periphery of said top wall opening and at the outer periphery of said movable part intermediate said dispensing and valve portions thereof.

3. The container closure as set forth in claim 1 wherein said retaining means comprises a bead inwardly extending from the periphery of said top wall opening and a mating groove therefor along the periphery of said movable part, said bead forming a gently downwardly inwardly sloped continuation of said top wall adjacent said top wall opening.
